R. C. KNOPKE,
METAL FENCE POST,
APPLICATION FILED OCT. 23, 1915.

1,237,654.

Patented Aug. 21, 1917.

INVENTOR:

Raymond C. Knopke

UNITED STATES PATENT OFFICE.

RAYMOND C. KNOPKE, OF GLENELLYN, ILLINOIS.

METAL FENCE-POST.

1,237,654.

Specification of Letters Patent. Patented Aug. 21, 1917.

Application filed October 23, 1915. Serial No. 57,453.

To all whom it may concern:

Be it known that I, RAYMOND C. KNOPKE, a citizen of the United States, and a resident of Glenellyn, county of DuPage, and 5 State of Illinois, have invented certain new and useful Improvements in and for Metal Fence-Posts, of which the following is a specification.

My invention relates to fence posts and 10 has particular reference to improvements in metallic posts for metal fences, *i. e.*, for the support of wire fencing.

The object of my invention is to provide a metallic post which shall furnish a reliable 15 and durable support for the fencing; that shall be adapted to be driven into the ground, as distinguished from the setting of a post in a post hole; that shall have great holding power and effectively resist and 20 oppose the displacing forces to which it is subjected; which shall be of simple and easily manufactured construction, and very inexpensive. Other objects of my invention will appear hereinafter.

25 My invention consists generally, in a metallic fence post of one or the other of the constructions and combinations of parts hereinafter described and particularly set forth in the appended claims.

30 The invention will be readily understood by reference to the accompanying drawings, which form part of this specification, and in which:

Figure 1 is a vertical elevation of a section of fencing containing metallic posts embodying my invention;—Figs. 2, 3, and 4 are perspective views of the lower or anchor-ports of my post, in three different forms;—Fig. 5 is a face view of a lower anchor plate, of the form shown in Fig. 2;—Fig. 6 is a side view of the lower part of the post showing a portion of the lower anchor plate and the whole of the upper anchor plate;—Fig. 7 is a sectional view of the 40 post shown in Fig. 2, the section being upon a plane above the upper anchor plate;—Fig. 8 is a similar plan section of the post shown in Fig. 3;—and Fig. 9 is a like view of the post depicted in Fig. 4.

50 In Fig. 1 I have shown two of my novel metal posts, A, A, as they appear after being driven into the ground, B. The wires, C, represent the fencing material, (whether simple wires or wire netting) fastened to 55 and supported by the posts.

In practice the metal posts are preferably steel or wrought iron, and are of sufficient strength to resist bending strains that would allow the destruction of the fence. The post proper, as indicated in Figs. 2, 3 and 60 4, may be T-shape or L-shape in cross section. My experience and observation lead me to give preference to the T-form shown in Figs. 2 and 4, over the angle or L-form, shown in Fig. 3. As will appear herein- 65 after, the specially novel parts are applica-ble to both T-bars and angle bars.

Whatever the shape of the bar, its lower end, A', is sharpened to facilitate the driv- 70 ing of the post into the ground. This sharp- ening is clearly shown in Figs. 2, 3, and 4.

The lower end of the post or bar, A, in each case, is driven into the ground to a depth of eighteen to twenty-four inches; and the portion thus embedded in the ground 75 is equipped with bracing or anchor plates by which the longitudinal and transverse areas of the post are greatly increased at points best adapted to resist strains tending to throw down the post. As also herein- 80 after explained, the plates are so formed as to make them effective against upward stresses tending to withdraw the posts from the ground.

The plate, D, which lies nearest to the 85 surface of the ground when the post is in position is formed from a flat plate of metal and has a straight, vertical edge, D', also a straight edge, D², that is preferably perpen- 90 dicular to the body of the post, and also an irregular edge, D³, about to be described. The straight edge of the plate lies against the inner side of the post and is secured to the lateral flange by means of rivets, D⁴, preferably two in number. The engagement 95 of the edge of the plate with the other flange of the post prevents twisting or rock- ing of the plate and in some cases I find it sufficient to fasten it with one strong rivet midway of the height of the plate.

The irregular edge, D³, is of such form 100 that the greatest areas for coaction with the ground are found at the lower end, D⁵, and at the upper end, D⁶, of the plate. This is in sharp contrast with the action of an 105 ordinary triangular plate; and my novel plate is much more effective. It will be noted that the inner bend or curve, D⁷, of the edge, D³, reduced the area of the middle portion of the plate and that the ma- 110

terial thus saved is added to the upper and lower portion of the plate. The triangular form alluded to is indicated by the dotted lines, D^s , of Fig. 6. It should be observed that the material usually lying against the face of the post at the lower end of the plate is done away with in my plate and is distributed or disposed in such a way as to increase the total effective area of the plate, measured from the edges of the face flange to which it is attached. But these are not the only advantages of this particular shape of the plate. A chief purpose in forming the plate as described is to provide for the easy first entrance of the lower end of the plate into the ground so as to reduce the resistance of the post to the driving action; and a second and equally important purpose is that the plate may thus easily be embedded in the ground that it cannot be bent by the further driving which sinks the wider part of the plate into the ground. In other words, the lower part serves as an easily driven guide for the upper part of the plate while the latter is displacing the earth laterally. Thus, after the plate is well set into the ground the wider portion of the plate though of greater area than found in any common triangular plate may safely be driven downward without danger of bending the plate or tearing it from the body of the post.

Below the lateral plate, D , I position the main anchor plate, E , securing it to the post rigidly by means of several rivets, E' . As explained hereinafter, I may form the upper edges of the plates, E , in various ways to make them effective as to anchors, but for the moment these differences may be disregarded in the consideration of the general form of the plate and the blank from which it is made. It is not of triangular form, but it is of a peculiar form that makes substantially the whole of the plate effective to brace the post, *i. e.*, the form is such that the least possible metal coincides with the face, A'' , of the post; and, for a given area and weight of metal, the greatest possible area is exposed beyond the outlines of the post. Thus, as appears in Fig. 5, the plate is virtually the double of the plate, D , and the curved edge of the latter is preserved in both of the edges, E^2 , E^2 , of the plate, E . By this formation the maximum exposed area is secured, and the plate is so shaped that it easily may be driven into the ground to the point at which the more widely extending portions of the plate may be safely driven without danger of distortion.

For convenience, I have given the name "double ogee" curve to the edges, D^s , and E^2 . To the lower end, E^s , of the plate, I have given the name "blunt end."

65 It should be observed that while the lower

end is actually blunt, its portions, E^4 , which extend out from the post, present relatively sharp driving edges to the ground.

I find that the best effects are secured by placing the blunt end of the plate, E , at 70 a distance from the lower end of the post, and preferably at a distance nearly equal to the height of the plate, E . The sum of all plate dimensions is such that when the post has been driven in the ground the upper edge, D^2 , of the plate, D , is buried beneath the surface of the ground, but obviously the relative dimensions and proportions illustrated may be modified in such manner that the top plate may remain 80 slightly exposed at the surface, or flush therewith.

I do not find any condition under which the plate, E , can be advantageously placed at the extreme lower end of the post. The 85 position illustrated is far better, for it insures the action of the plate, E , as a fulcrum for the parts of the post within the ground and thus prevents any considerable displacement of the post in a plane perpendicular to that of the fencing. The plate, D , of the post has its position at, or slightly beneath, the surface of the ground in order that it may act as a fulcrum between the parts of the post beneath and 90 above the ground, as required to resist most effectively the tendency of the fence to move longitudinally in its plane.

Plain plates disposed, as here shown, have a considerable anchoring effect by reason of 100 the compression of the earth around them and their frictional engagement therewith. But I have observed that when a metal post equipped with plain surface plates is only slightly loosened in the ground, the post 105 may be withdrawn quite readily. It is desirable, therefore, that the post shall be well anchored, to resist any tendency toward dislodgment. I have also observed that in many cases a great upward strain is exerted 110 upon the posts by the fencing, particularly when fencing extends across hollows. The post has a tendency to pull out of the ground also where soil is loose and sandy, and therefore an effective anchorage is most desirable 115 and very necessary. To this end I widen the top edge or edges of the lower plate, and by the peculiar constructions disclosed I accomplish this without either weakening the plate or increasing its size, or its weight, 120 and without making it specially difficult to drive.

The kind of lateral distortion which I find to yield the best results in the case of the lower plate, consists in the opposite off-setting of adjacent portions or its upper edge, in one or the other of the forms shown in Figs. 2, 3, and 4. Each of these forms many times increases the effective width of the top of the plate; and, obviously, when 125

buried in the earth these wide edges oppose the lifting of the post. In all forms the offsets are positioned at the top of the plate and do not begin to enter the ground until the widest part of the plate has already entered the ground and is thus positioned to oppose its displacement by the lateral forces put in action by the driving of the offset portions into the earth.

10 Perhaps the most simple form of offsets is that depicted in Fig. 3. In that case, I first cut a notch, F, in the top of the plate, E, making the notch of the width of the face of the post. I then oppositely offset the edges, E'. To merely offset these edges in straight lines is desirable, but, on the other hand, is rarely sufficient; for such edges tend to straighten or flatten into the plane of the remainder of the plate when opposed by solid earth. To avoid this I form the edges, E', as curved bends or crimps, E'', thereby giving them an inherent strength aside from the strength of their connection with the body of the plate.

25 A stronger formation is depicted in Fig. 2 wherein it will be seen that the top offsets, G—G, are integrally connected, there being no notch in the plate. Instead, integral bends, G', join the offsets to the middle portion, G'', of the plate. This arrangement of integral offsets greatly strengthens the upper edge of the plate.

In lieu of the opposite offsets depicted in Figs. 2 and 3, I sometimes use a plate, E, 35 having a fluted upper edge, H, composed of opposite V-shaped offsets, H', as best shown in Fig. 9. This formation is limited to the upper portion of the plate and provides the desired wide top or upper edge.

40 Preferably, I do not crimp, flute or otherwise laterally distort the upper edge of the plate, D, for the reason that that edge of the plate is not deeply buried in the ground and any shape other than a straight, flat shape 45 would merely serve to leave the ground in loose condition, while it should be left in the most tightly packed and stable condition.

Posts constructed in accordance with my invention, possess great strength and stability and are very durable and yet may be made of relatively small total weight. It will be clear to those skilled in the art that my novel posts do not involve the use of specially skilled labor or large amounts of material and are, therefore, very inexpensive as compared with posts of like dimensions and strength now in use.

Having thus described my invention, I claim as new and desire to secure by Letters 60 Patent:—

1. The improvement herein described,

comprising a fence post composed of a body portion having a metal plate attached thereto, said plate being provided with cutting side edges, and with an upper edge out-turned at less than a right angle, whereby the post may be driven into the earth and carry the said plate below the surface thereof, substantially as described.

2. The improvement herein described, 70 comprising a fence post composed of a body portion having a metal plate attached thereto, said plate being provided with inclined cutting side edges and having its upper edge laterally and oppositely offset at opposite sides of the body portion, said offset portions having upwardly inclined faces, whereby the post may be driven into the earth completely covering the said plate, 75 substantially as described.

3. The improvement herein described, comprising a fence post composed of a metal bar, in combination with upper and lower anchor plates oppositely disposed and fixed to said bar at an angle to each other, one of said plates having an upper edge out-turned at less than a right angle, whereby the post may be driven into the earth and carry the said plate into the surface thereof, substantially as described.

4. The improvement herein described, comprising a metal fence post, of a flanged metal bar in combination with a flat metal plate fixed upon one of the flanges of the bar at substantially ground level height, said 95 plate projecting beyond the flange of the bar in the form of an upwardly and outwardly extending double ogee curve, and a lower anchor plate, having two double ogee curved cutting edges, secured flatwise upon another 100 flange of the bar substantially at right angles to the first mentioned plate, said lower plate being provided with an outwardly turned upwardly inclined top edge portion at either side of the bar, substantially as and 105 for the purposes set forth.

5. The improvement herein described, comprising a metal fence post composed of a flanged metal bar, in combination with an anchor plate fixed to the lower part of said 110 bar and having its upper part laterally and oppositely distorted to provide upwardly inclined portions at opposite sides of the bar, whereby the post may be driven into the earth to a point completely covering said 115 inclined portions, the distorted portion of the plates being integrally joined and thus strengthened, substantially as and for the purposes described.

In testimony whereof, I have hereunto set 120 my hand this 20th day of October, 1915.

RAYMOND C. KNOPKE.
